US00D472823S

(12) **United States Design Patent** (10) Patent No.: **US D472,823 S**
(45) Date of Patent: ** Apr. 8, 2003

(54) **MAGNETIC LOCATOR**

(75) Inventors: **Duard Wilson**, Kankakee, IL (US);
Russell Forbes, Chicago, IL (US);
Jeffrey Bransky, Chicago, IL (US);
Robert Sheldon, Chicago, IL (US);
Gregory Foster, Chicago, IL (US)

(73) Assignee: **Chicago Steel Tape Company**,
Watseka, IL (US)

(**) Term: **14 Years**

(21) Appl. No.: **29/160,531**

(22) Filed: **May 10, 2002**

(51) LOC (7) Cl. **10-04**

(52) U.S. Cl. **D10/46**

(58) Field of Search D10/46, 78; 324/66,
324/67, 327, 329, 345, 326; 340/551, 572

(57) **CLAIM**

The ornamental design for a magnetic locator, as shown and described.

DESCRIPTION

FIG. 1 is a top view of a new design for a magnetic locator according to our invention;

FIG. 2 is a perspective view illustrating the top, left and rear view thereof;

FIG. 3 is a rear view thereof;

FIG. 4 is a front view thereof;

FIG. 5 is a left view thereof; and,

FIG. 6 is another perspective view illustrating the top, front and left view thereof.

1 Claim, 3 Drawing Sheets
